United States Patent Office.

WILLIAM J. CONNELL, OF WEST UNITY, OHIO.

Letters Patent No. 91,607, dated June 22, 1869.

IMPROVEMENT IN FLOOD-ROLLER.

The Schedule referred to in these Letters Patent and making part of the same.

To all whom it may concern:

Be it known that I, WILLIAM J. CONNELL, of West Unity, in the county of Williams, and State of Ohio, have invented a new and useful Improvement in Flood-Rollers; and I do hereby declare that the following is a full and exact description thereof, reference being had to the accompanying drawings, and to the letters of reference marked thereon.

My invention consists in a hollow octagon roller, in combination with two slotted posts, or uprights, for the purpose of a flood-roller.

The accompanying drawing represents an isometric perspective of my improved flood-roller.

In the construction and arrangement of my flood-roller, it is necessary to employ two posts, B, with slots, B', to receive the axis of the roller.

These posts may be framed into mud-sills, A, which may also be connected by a cross-sill, A'.

Braces, D, are set on the lower side of the posts, and the mud-sills may be held by a stone or block, C, to prevent swagging. But the mud-sills are not essential, as the posts may be set firmly in the ground.

The roller, G, is made with eight sides and angles, so that the current of water, striking against the same, will give the roller a rotary motion. It may be made hollow, out of inch boards, so that the roller will easily float on the water, and rise and fall with the stream.

The axis of the roller is placed loosely in the slots B', and slides freely up and down in these slots as the roller rises and falls with the water.

The roller may be made, usually, about two and a

half to four feet in diameter, but the size may be varied at pleasure, according to circumstances, and the condition of the stream where the roller is to be used.

On two opposite, or nearly opposite sides of the roller, may be made openings, or spaces, H, say about an inch wide, for the escape of sand, which will thus be washed out as the water falls.

The above-described roller is very cheap and durable. It will draw flood-wood, and everything afloat, immediately under it, thus allowing nothing to accumulate, or catch against and damage the roller, or obstruct the stream.

This roller forms a complete fence against all kinds of stock.

I do not limit my claim to an octagon roller, as a six-sided roller, or any other polygon roller, may be used; but I prefer the roller above described.

I do not broadly claim the separate devices above described, but I believe the above arrangement of roller is an improvement over anything heretofore known.

Having thus fully described my invention,

What I claim, and desire to secure by Letters Patent of the United States, is—

The above-described octagon, or polygon roller, in combination with the slotted posts, substantially in the manner and for the purposes set forth.

WILLIAM J. CONNELL.
